UNITED STATES PATENT OFFICE.

JACOB H. LING, OF DETROIT, MICHIGAN.

REPEATING PHONOGRAPH.

1,418,584.

Specification of Letters Patent. Patented June 6, 1922.

Application filed December 29, 1920. Serial No. 433,865.

To all whom it may concern:

Be it known that JACOB H. LING, a citizen of the United States of America, residing at Detroit, in the county of Wayne and State 5 of Michigan, have invented certain new and useful Improvements in Repeating Phonographs, of which the following is a specification, reference being had therein to the accompanying drawings.

10 This invention relates to a repeating phonograph.

The invention consists in the structural features and arrangements of parts herein-after fully described and illustrated in the 15 accompanying drawings wherein;

Figure 1 is a plan view of the improved phonograph;

Figure 2 is a vertical sectional view taken on line 2—2 of Figure 1; and showing the 20 mechanism of the phonograph in front elevation;

Figure 3 is a horizontal sectional view taken on line 3—3 of Figure 2;

Figure 4 is a vertical sectional view taken 25 on line 4—4 of Figure 3 and showing the parts of the phonograph in side elevation.

Figure 5 is a vertical section on line 5—5 of Figure 3, illustrating certain air passages;

30 Figure 6 is a vertical section taken on line 6—6 of Figure 3 showing certain valve mechanism carried by a swinging arm;

Figure 7 is a vertical section on line 7—7 of Figure 3 showing a pneumatic action.

35 In these views the reference character 1 designates the casing of a phonograph, 2 the turn-table thereof, 3 a record resting on said turn-table, 4 a motor for driving the turn table, 5 a tone arm mounted to swing both 40 vertically and horizontally, 6 the sound box carried by said tone arm and 7 the reproducing needle carried by said sound box, all of said parts being combined in the usual well known manner. Adjacent the swivel end 45 of the tone arm a rod 8 projects upwardly through the casing 1 and rigidly carries the horizontal arm 9 extending beneath the tone arm 5, carrying a pair of upstanding pins 10 normally engaging at each side of the tone 50 arm. The rod 8 extends downwardly within the casing 1 to engage a bearing member 11 secured to the casing bottom. Pneumatics 12 and 13 are reversely secured to the bearing block 11, one at each side thereof, said 55 pneumatics being employed respectively to raise the rod 8 and arm 9 and thus lift the

tone arm, and to rock said rod when in raised position to swing the tone arm outwardly. The pneumatic 12 carries an arm 14, which upon collapse of said pneumatic, 60 exerts an upthrust upon the rear end portion of the horizontal pin 15 rigidly carried by the rod 8, and the pneumatic 13 upon collapsing exerts a horizontal thrust through a push rod 16 upon the forward end of said 65 pin to rock the rod 8 and thus swing the tone arm outwardly. Exhaustion of the two pneumatics 12 and 13 is effected by a relatively large pneumatic 17 which in turn is adapted to be exhausted through a flexible 70 tube 18 by a bellows pump 19 driven by the motor 4. Said pump may be driven through any suitable mechanism, but it is preferred to mount a cam 20 upon a shaft 21, driven by the motor 4, which cam engages a roller 75 22 upon an arm 23 operatively connected to said pump. The pneumatic 17 is adapted to exhaust the two pneumatics 12 and 13 through a flexible tube 24 in constant communication with said pneumatics 12 and 13 80 through passages 24^a and 24^b formed in the bearing member 11. Provision is made for varying the restriction of the passage 24^a leading to the pneumatic 13 by a screw 24^c threaded into the bearing member 11 and 85 having its lower end intersecting said passage 24^a. The connection established through the tube 24 is under a primary and secondary control to provide for proper energization of the pneumatics 12 and 13 in predetermined 90 positions of the tone arm.

Describing first the primary control, 25 is a forwardly projecting arm mounted fast upon the lower end of the rod 8 and carrying at its forward end a valve block 26 which 95 may be formed of wood or some other suitable material. For accommodation of said arm, the bearing member 11 is apertured as indicated at 27.

As is best disclosed in Figure 6, the block 100 26 is formed with a longitudinal passage 28 which is transversely intersected by a valve 29 having the nature of a pin adapted to under-go a restricted sliding movement. The extremities of said pin respectively 105 carry buttons 30 and 31, which through engagement with the sides of the block 26 limit the stroke of said valve 29. When the button 30 presses against the block 26, a port 32 transversely piercing the valve 29 is registered with the passage 28 so that the end 110 portions of said passage are in communica-

tion. When the other button 31 is pressed against said block, an imperforate portion of said valve registers with the passage 28 closing the same. The valve 29 is adapted 5 to be shifted between its two limiting positions by engagement of the buttons 30 or 31 with two adjustable blocks 33 having aligned grooves 34 in their top ends engaging a horizontal guide rod 35 and having 10 similar bottom grooves engaging a guide rod 36 which is in the nature of a crank having pivotal end portions 37 adapted to swing vertically. A pair of coil springs 38 exert an upward thrust upon the guide rod 36, 15 said springs being set in suitable sockets in the base plate 39 which supports the bearing member 11 and pneumatics 12 and 13 in unitary relation. The springs 38 act to clamp the blocks 33 between the fixed and 20 movable guide rods 35 and 36 in various spaced relations as will presently be made clear. In accomplishing this result said springs overcome the effort of a pair of V-shaped wire springs 40 which constantly 25 urge the blocks 33 toward each other. Through exertion of a slight pressure upon the exposed upper end of the rod 8 the springs 38 may be overcome, said pressure being transmitted to the moveable guide rod 30 36 by the arm 25 and block 26. Under such conditions the blocks 33 are urged by the springs 40 into opposite contact with the valve block 26. When the arm 25 is swung through an arc by rocking of the rod 8, the 35 block 33 toward which said arm is swung is adjusted away from the companion block 33 by pressure of said arm and will maintain its adjusted position by virtue of the clamping springs 38 subsequent to return of 40 the arm 25 to its initial position. The passage 28 in the block 26 is open at one end and at its other end is in communication with a flexible tube 41.

Describing now the secondary control for 45 the connection established by the tube 24, 42 is a pneumatic action which surmounts the pneumatic 17, and which comprises a rectangular block built up preferably of several strips to facilitate manufacture. Said block 50 is interiorly formed with three chambers 43, 44 and 45 arranged one above another. The intermediate chamber 44 is in communication with the pneumatic 17 by a passage 46 while the upper chamber 43 is connected by 55 a passage 47 with the tube 24. Communication between the upper and intermediate chambers is controlled by a disk valve 48 having the depending stem 49. Between said intermediate chamber and the lower- 60 most chamber 45 there is interposed a dia- phragm 50 formed of sheet rubber or other suitable material and within the chamber 44 there is centrally secured to said diaphragm a thrust bearing 51 engaging the lower end 65 of the stem 49. The chamber 45 is connected

by a passage 52 with the flexible tube 41 which leads to the valve block 26. A minute passage or bleeder 53 connects the intermediate and lower chambers and a similar restricted passage 54 opens from the upper 71 passage 43 to the atmosphere.

With the turn table 2 there is associated an automatic braking device comprising a lever 55 intermediately pivoted in a bearing 56 surmounting the casing, one end of said 75 lever being provided with a brake member 56a adapted to frictionally engage under face of the turn table adjacent the periphery thereof and the other lever extremity being bent through a right angle as indicated at 80 57 to form a rest for the sound box. Thus, the weight of the sound box and tone arm upon the bent extremity of said lever is caused to act through said lever to exert a braking pressure upon the turn table so as 85 to hold the latter stationary when said lever is engaged by the sound box.

Considering now the operation of the described invention, when it is desired to repeat a record or a portion thereof, the tone 90 arm is first shifted to dispose the needle in starting position, (ordinarily in the outermost groove of the record). A slight pressure is then exerted upon the projecting upper end of the rod 8. Finally the tone arm 95 is shifted to dispose the needle at the point terminating the rendition which is to be repeated (this point ordinarily being the innermost groove of the record.) It is to be understood that while these preliminary adjustments of the tone arm are being made the same will be engaged between the pins 10 on the arm 9 so that the latter will swing in unison with said arm. By depressing the rod 8 after the tone arm is in initial position for 100 reproducing, the two blocks 33 are relieved from the clamping pressure of the springs 38 and responsive to the effort of the springs 40 said blocks are shifted into contact with the valve block 26. When subsequently the tone 105 arm is adjusted to its final reproducing position, the rod 8 is rocked by the arm 9 and the resultant rocking of the arm 25 shifts the left hand block 33 to a position corresponding to the final position of the tone arm. The parts 110 are now properly set for repeating and the tone arm is adjusted in its initial position and the motor started. As the tone arm is gradually fed inwardly through engagement with the record the rod 8 is correspondingly 115 rocked so that the valve block 26 gradually approaches the left hand block 33. As the tone arm reaches its final position of playing, the left hand block 33 through engagement with the button 30, shifts the valve member 29 to register the port thereof with the passage 28. This places the lowermost chamber 45 of the pneumatic action in free communication with the atmosphere. At this time the pneumatic 17 will be collapsed ow- 125

ing to the exhaustion thereof by the bellows pump 19, the exhaustion having been taking place during the inward shifting of the tone arm upon the record. The chamber 44 will 5 also be exhausted since the latter is in open communication with said pneumatic 17 by the passage 46. Prior to admission of air, as just described, to the lower chamber 45, the latter will also have been exhausted owing 10 to connection of the same by the bleeder passage 53 with the intermediate chamber. When air is admitted to the chamber 45, the pressure differential thus created between said chamber and the intermediate chamber 15 results in an upper deflection of the diaphragm 50, resulting in unseating of the valve 48 (owing to engagement of the stem of said valve by the thrust-bearing 51). Unseating of said valve establishes connection 20 between the upper and intermediate chambers 43 and 44 and consequently connects the tube 24 and pneumatic 17. Thus exhaustion of the two pneumatics 12 and 13 is accomplished through the connection 24 and the 25 pneumatic 12 on collapsing acts through the arm 14 upon the pin 15 to raise the rod 8 and thereby lift the tone arm and needle clear of the record. The pneumatic 13 on collapsing acts through the push rod 16 upon the 30 pin 15 to rock the rod 8 and thereby return the tone arm to its initial position. The action of the pneumatic 13 must be somewhat retarded beyond that of the pneumatic 12 so that there may be no tendency to swing the 35 tone arm outwardly until the same has been raised clear of the record. This effect is secured by adjusting the screw 24^c to increase the resistance of the portion of the passage 24^a leading to the pneumatic 13 to a predetermined extent beyond the portion of said 40 passage leading to the pneumatic 12. Thus exhaustion of the pneumatic 13 is accomplished somewhat more slowly than that of the pneumatic 12, securing the desired retardation in actuation of the rod 8 by the 45 pneumatic. As the tone arm reaches its initial playing position under impetus of the pneumatic 13 the right hand control block 33 is encountered by the button 31. This results 50 in shifting of the valve 29 to its position closing the port 28 and consequently the lowermost chamber 45 with the pneumatic connection is cut off from the atmosphere. An equalization of the pressure in said chamber 55 and the intermediate chamber immediately takes place due to the connection established by the bleeder passage 53 and the valve 48 returns to its seat. Expansion of the two pneumatics 12 and 13 immediately follows 60 due to admission of air to the upper chamber 43 through the bleeder passage 54 and thence through the tube 24 to said pneumatics. Expansion of the pneumatic 12 permits lowering of the rod 8 and engagement of the tone 65 arm and needle with the record in starting

position. Expansion of the pneumatic 13 does not effect the rod 8 or the tone arm. This follows from the provision of a lost motion in the engagement of the push rod 16 with said pneumatic and with the arm 25 as 70 is clearly disclosed in Figure 2.

It is a further feature of the invention that provision may be made for automatic return of the tone arm to its outermost position and automatic braking of the turn 75 table in said position. Thus, if it be desired to stop the machine after playing of a record or a portion thereof, the tone arm is initially placed upon the brake lever, 55. Pressure is then momentarily exerted upon the 80 upper end of the rod 8 so that the valve control blocks 33 will be shifted against the valve block 26. The tone arm is then shifted to the final playing position causing the arm 25 and block 26 to correspondingly 85 shift the left hand block 33. The position of the right hand control block 33 will now correspond to the position in which the tone arm rests upon said brake lever so that when the tone arm is automatically swung outwardly, this movement will carry the sound box clear of the turn table and allow the 90 same to settle down upon the braking lever.

It is a desirable feature of the described invention that a very small portion of the 95 mechanism accomplishing repeating is exposed above the phonograph casing, said exposed portion comprising merely the upper end of the rod 8 and the arm 9 carried thereby. It is a further desirable feature of the 100 invention that apart from the preliminary shifting of the tone arm first to its initial position and then to its final position, no manipulation is necessary to set the device for repeating other than the exertion of a 105 slight pressure upon the upper end of the rod 8.

What I claim as my invention is:

1. In a phonograph, the combination with the tone arm thereof, of an arm engaging the 110 tone arm for automatically shifting the latter outward, a vertical rod carrying said arm, a pneumatic arranged to lift said rod, a second pneumatic arranged to rock said rod and thereby shift the tone arm outwardly, 115 means for exhausting said pneumatics, means for relatively retarding exhaustion of the rod rocking pneumatic, a valve controlling exhaustion of said pneumatics, and means for operating said valve by said rod in predetermined position of the latter.

2. In a phonograph, the combination with the tone arm thereof, of a vertical rod having the nature both of a rock shaft and plunger, a connection between said rod and 125 tone arm for lifting the latter clear of a record by functioning of said rod as a plunger and for swinging said rod outwardly through functioning of said rod as a rock shaft, a pair of pneumatics respectively 130

adapted to raise and rock said rod when collapsed, a rock arm carried by said rod, a valve member carried by said arm, a pair of control members for said valve member disposed at each side of said valve member, 5 adjustable to and from each other, means yieldably holding said control means adjusted, air exhausting means, a connection from said exhausting means to said pneumatics, 10 means for controlling said connection by said valve, and means for retarding the exhaustion of the rod rocking pneumatic beyond that of the rod lifting pneumatic.

3. In a phonograph, the combination with 15 the tone arm thereof of a vertical rod functioning both as a rock shaft and plunger member, a connection between said rod and the tone arm for lifting the latter clear of the record through functioning of said rod 20 as a plunger and for swinging the tone arm outwardly through functioning of said rod as a rock shaft, a pair of pneumatics respectively adapted to raise and rock said rod through collapsing, air exhausting means, a 25 tubular connection between said means and said pneumatic, a movable valve member controlling said connection, means for effecting movement of said valve member through rocking of said rod and a pair of control 30 members for said valve member, adjustable relative to the latter to be engaged thereby in various positions thereof.

4. In a phonograph, the combination with 35 the tone arm thereof, of a vertical rod functioning both as a plunger and rock shaft, a connection between said rod and tone arm for lifting the latter, through functioning of the rod as a plunger and for swinging the tone-arm through functioning of the rod 40 as a rock shaft, a pair of pneumatics associated with said rod, a pin carried by said rod, an arm projecting from one of said pneumatics and engaging said pin to exert an up-thrust thereupon when the pneumatic

collapses, a push rod connecting the other 45 pneumatic to said pin for rotatively actuating the rod upon collapse of said pneumatic, air exhausting means, a tubular connection between said means and said pneumatics, a valve controlling said connection and adjustable control means for said valve.

5. In a phonograph, the combination with 50 the tone arm thereof, of a vertical rod functioning alternatively as a plunger and rock shaft, a pair of pneumatics respectively 55 adapted for raising and rocking said arm when collapsed, air exhausting means, a tubular connection between said means and said pneumatics, a rock arm carried by said rod, a valve carried by said rock arm 60 controlling said tubular connection, a pair of sliding control members for said valve arranged one at each side of said rock arm, means yieldably urging said control members toward each other, stronger means 65 yieldably resisting movement of the control members responsive to the first-mentioned means, and means to relieve the control members therefrom when pressure is downwardly exerted upon said rod.

6. In a phonograph, the combination with 70 the tone arm and casing thereof, of a rock arm within said casing, means for actuating said rock arm from said tone arm, a pair of pneumatics for respectively raising and swinging the tone arm, air exhausting means, a tubular connection between 75 said means and said pneumatic, a valve controlling said connection carried by said rock arm, a pair of control members for said valve 80 arranged one at each side of said rock arm, a pair of guide rods for said control members functioning further as clamping members to hold the control members variously adjusted, means yieldably urging said control members toward each other.

In testimony whereof I affix my signature.
JACOB H. LING.
